CLAIM

I claim the ornamental design for a portable carrier, as shown and described.

DESCRIPTION

FIG. 1 is a right perspective view showing a portable carrier showing my new design;

FIG. 2 is another right perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines shown in FIG. 1 are included for the purpose of illustrating environment and form no part of the claimed design.
